Fig. 3

Fig. 7

Fig. 4

FIG. 1 is a plan view of an instrument holder showing my new design;

FIG. 2 is a rear elevational view of the instrument holder of FIG. 1;

FIG. 3 is a front elevational view of the instrument holder of FIG. 1;

FIG. 4 is a side elevational view of an instrument holder showing my new design;

FIG. 5 is a plan view of an instrument holder showing a modified form thereof;

FIG. 6 is a rear elevational view of the instrument holder shown in FIG. 5; and

FIG. 7 is a front elevational view of the instrument holder shown in FIG. 5.

I claim:

The ornamental design for an instrument holder, substantially as shown and described.
